US00D507248S

(12) **United States Design Patent** (10) Patent No.: **US D507,248 S**
Hisashi et al. (45) Date of Patent: **** Jul. 12, 2005**

(54) **SEMICONDUCTOR CARRIER**

(75) Inventors: **Minoru Hisaishi**, Tokyo (JP); **Noriyuki Matsuoka**, Tokyo (JP); **Takeyuki Suzuki**, Tokyo (JP)

(73) Assignee: **Yamaichi Electronics Co., Ltd.**, Tokyo (JP)

(**) Term: **14 Years**

(21) Appl. No.: **29/210,045**

(22) Filed: **Jul. 27, 2004**

(51) LOC (8) Cl. **13-03**

(52) U.S. Cl. **D13/182**

(58) Field of Search D13/182; 257/666, 257/669, 675, 676; 324/755

(57) **CLAIM**

The ornamental design for a semiconductor carrier, as shown and described.

DESCRIPTION

FIG. 1 is a top plan view of a semiconductor carrier of our new design in its entirety;

FIG. 2 is a bottom plan view of our new design;

FIG. 3 is a right end view of our new design;

FIG. 4 is a left end view of our new design;

FIG. 5 is a front view of our new design;

FIG. 6 is a rear view our new design; and,

FIG. 7 is a left, front perspective view of our new design.
